By Wallace R. Lane. *W.R.L.*

UNITED STATES PATENT OFFICE.

HUDSON A. TEDMAN, OF GALESBURG, ILLINOIS, ASSIGNOR TO WINSLOW BOILER & ENGINEERING CO., OF GALESBURG, ILLINOIS, A CORPORATION OF ILLINOIS.

FIRE POT FOR FUEL BURNERS.

Application filed November 20, 1924. Serial No. 751,007.

This invention relates to improvements in fire pots for fuel burners, and has for its object to provide a device of that character comprising a main shell formed of steel, or 5 the like, and supplemented by a refractory lining so located as to receive the maximum heat to prevent deterioration of the shell.

This and other objects will be more fully described in the following specification and 10 shown in the accompanying drawing, in which—

Fig. 1 is a plan view of my improved construction.

Fig. 2 is a vertical section taken along the 15 line 2—2 of Fig. 1.

10 indicates generally the shell of a fire pot, generally of circular form, having the side wall 10^a inclined from bottom to top, and with inlet openings 10^b and 10^c at one 20 side, also the passages 10^d and 10^e at either side of the ports 10^b and 10^c. These ports and passages are provided to permit injection or entrance of the fuel, air, pilot light, or the like. At its upper portion the side 25 wall 10^a is offset to provide the horizontal shoulder 10^f and the vertical wall portion 10^g. Detachably mounted upon the shoulder 10^f is the refractory ring or collar 11 constructed of suitable refractory material, and 30 having its inner periphery inclined inwardly from bottom to top as indicated by numeral 11^a, to generally continue the surface of the lower portion of the fire pot chamber.

In practice the fuel is injected or otherwise supplied to the fire pot chamber and 35 circulated thereabout during or after combustion. The tendency of the burning fuel or fuel mixture is to rise, and the maximum heat zone is at the upper portion, so that the 40 deterioration effect thereof is received by the refractory ring 11, which thus prevents deterioration of the surrounding metal shell, and to an appreciable extent reduces the heat transmitted therethrough. At the same time 45 this refractory ring when heated is not so

susceptible to quick cooling, and serves to equalize the heat adjacent the zone of atomization and combustion.

When necessary the refractory ring may be readily replaced with little expense and 50 no inconvenience.

It will be obvious that my invention is susceptible of modification and improvement, and I do not wish to be restricted to the form shown and described, except as defined in 55 the appended claims.

What I claim is:

1. A fire pot for fuel burners comprising a metal fire pot shell having an open top portion, and a ring of refractory material 60 the inner end of the bore of which registers with the bore of said open top, said ring being supported wholly above the pot and positioned approximately in the zone of most intense heat normally developed by the burner in operation, the bore of said ring being of approximately the same diameter as the interior of the shell and the surface of said bore forming an approximate continuation of the inner surface of said shell. 70

2. A fire pot for fuel burners comprising a metal fire pot shell having an open top portion, said shell having outwardly offset portions contiguous to the open top portion, and a ring of refractory material having its 75 bottom face resting upon said offset portions and its bore at the inner end thereof in register with said top opening, said bore being of approximately the same diameter as the interior of the shell and the surface of 80 the bore forming an approximate continuation of the inner surface of said shell, said ring being wholly supported above the pot and positioned approximately in the zone of most intense heat normally developed by the 85 burner in operation.

In witness whereof, I hereunto subscribe my name to this specification.

HUDSON A. TEDMAN.
